[57] **CLAIM**

The ornamental design for a touch dial key pad speaker telephone for a "clean room" or the like, as shown and described.

DESCRIPTION

FIG. 1 is a front elevational view of a touch dial pad speaker telephone for a "clean room" or the like showing my new design; and,

FIG. 2 is a right side elevational view thereof, the left side elevational view, and the top and bottom plan views are identical to the right side elevational view thereof.

The broken line showing of environmental structure is for illustrative purposes only and forms no part of the claimed design.
